UNITED STATES PATENT OFFICE.

LEWIS B. JEFFCOTT, OF NEW YORK, N. Y.

FOLDING BED.

1,037,259.

Specification of Letters Patent. Patented Sept. 3, 1912.

Application filed November 23, 1910. Serial No. 593,823.

To all whom it may concern:

Be it known that I, LEWIS B. JEFFCOTT, a citizen of the United States, and a resident of the city of New York, borough of Manhattan, in the county and State of New York, have invented a new and Improved Folding Bed, of which the following is a full, clear, and exact description.

The object of the invention is to provide 10 a new and improved folding bed arranged to permit of conveniently folding the bed longitudinally into a comparatively small bundle and to allow of extending the bed for use without danger of accidental collapsing. For the purpose mentioned, the 15 mattress frame is made in sections, of which the head and foot sections are U-shaped and the middle or intermediate section is formed of side bars pivotally connected with 20 the side bars of the head and foot sections, and pivotal connections are provided between the head and foot sections and the head and foot of the bed.

A practical embodiment of the invention 25 is represented in the accompanying drawings forming a part of this specification, in which similar characters of reference indicate corresponding parts in all the views.

Figure 1 is a perspective view of the bed 30 in an extended position; and Fig. 2 is a sectional side elevation of the same arranged as a couch, also showing in dotted lines the sections of the bed frame folded when the bed or couch is not in use.

35 The folding bed illustrated in Figs. 1 and 2 consists essentially of a head A, a foot B and a mattress frame C provided with a mattress D of the usual construction. The mattress frame C consists of a head section 40 C', a foot section C² and an intermediate section C³, the sections C' and C² being U-shaped, and the middle or intermediate section C³ being formed of side bars pivotally connected by links E and E² with the side 45 bars of the head and foot sections C' and C². The links E on the opposite sides of the mattress frame are connected with each other by a cross bar E', and the links E² are provided with depending legs E³ adapted 50 to rest on the floor and connected with each other by a cross bar E⁴.

The head A preferably consists of sides A' connected with each other by cross bars A² and A³, and the links E are pivotally 55 connected with the forward ends of the sides A' by removable bolts F, so as to per-

mit of detaching the mattress frame C from the head A whenever it is desired to fold the bed, as indicated in dotted lines in Fig. 2. The free or upper end of the head section C' of the mattress frame C is adapted to rest on the cross bar A³ of the head A, and the said head section C' is provided with notched links G adapted to engage the cross bar A³ to hold the head section C' in an inclined position, as indicated in dotted lines in Fig. 1.

The foot section C² of the mattress frame C is connected with the foot B by the use of two pairs of links H and H' pivotally connected with the side bars of the foot section C² and the legs of the foot B, as plainly indicated in Fig. 1. The links H and H' are of different length, and the upper link H is so arranged as to form a support 70 for the foot section C² to rest on, while the link H' forms a brace. Now by the arrangement described, the mattress frame C is supported on the cross bar A³, the bolts F, the legs E³ and the links H, so that an 75 exceedingly firm support is given to the mattress frame. It will also be noticed that by the arrangement described the mattress frame C can be detached from the head A on removing the bolts F, and the mattress 80 frame with the foot B folded up in a comparatively small bundle to allow convenient storing of the bed while not in use.

The side rails of the foot section C² of the mattress frame C are provided with hooks 90 I adapted to engage buttons J attached to the sides A' of the head A, with a view to support the middle section C³, the foot section C² and the foot B in a folded position, as indicated in Fig. 2, whenever it is desired 95 to convert the bed into a couch, the said parts then forming the back of the couch, while the mattress section C' forms the seat of the couch.

Having thus described my invention, I claim as new and desire to secure by Letters Patent:

1. A folding bed, comprising a mattress frame formed of U-shaped head and foot sections and intermediate side bars, links 105 pivotally connecting the intermediate side bars with the head and foot sections, the links connecting the side bars and head section being connected together and the links connecting the said side bars and foot sections being provided with legs, a head 110 formed of two U-shaped side members con-

nected together and between which the head mattress section extends and rests on the connection between said members, the side members of the head being pivoted to the 5 links connecting the side bars and head mattress section, and a foot pivotally connected with the foot mattress section.

2. A folding bed, comprising a mattress frame formed of U-shaped head and foot 10 sections and intermediate side bars, links pivotally connecting the intermediate bars with the head and foot sections, the links connecting the side bars and head section being connected together and the links connecting the said side bars and foot section being provided with legs, a head formed of 15 two connected U-shaped side members between which extends the head mattress section, the side members of the head being 20 provided with buttons and pivoted to the links connecting the side bars and head section, a foot pivotally connected with the foot mattress section, and hooks on the foot mattress section for engaging the buttons 25 on the side members of the head, when the foot mattress section and the intermediate bars are folded to form a back.

3. A folding bed, comprising a mattress frame formed of three pivotally connected 30 sections, the head and intermediate sections being connected together by links connected with each other by a cross bar, a head formed of two U-shaped side members connected together by a cross bar and between 35 which extends the head section with its outer end resting upon said cross bar, the side members of the head being provided with buttons and pivoted to the links connecting the head and intermediate mattress sections, 40 a foot pivotally connected with the foot mattress section, and hooks carried by the foot mattress section and adapted to engage the said buttons when the foot and intermediate and foot mattress sections are folded to form 45 a back.

4. In a folding bed, a mattress frame

formed of U-shaped head and foot sections and intermediate side bars pivotally connected with the foot section, links connected with each other and pivotally connecting 50 the side bars with the head mattress section, and a head formed of two U-shaped side members connected by cross bars and between which the head mattress section extends with its outer end resting upon the 55 upper cross bar; the said side members of the head being pivoted to the said links.

5. In a folding bed, a mattress frame formed of U-shaped head and foot sections and intermediate side bars pivotally connected with the head section, links connected with each other and pivotally connecting the side bars with the foot mattress section, and a head formed of U-shaped 60 connected side members between which the 65 head mattress section is confined and supported.

6. A convertible bed and couch, comprising a head having connected side rails, a foot, a mattress frame having a head section, 70 a foot section and an intermediate section, the sections being pivotally connected with each other at the sides, the head section of the frame being pivoted on the said head, pairs of links connecting the foot with the 75 said foot section of the frame, a leg pivotally connected with the joint of the foot section and the intermediate section of the mattress frame, a support on the said head for the free end of the head section of the 80 frame to rest on, and notched braces hung on the said head section of the frame and adapted to engage the said support to hold the head section of the frame in an inclined position.

In testimony whereof I have signed my name to this specification in the presence of two subscribing witnesses

LEWIS B. JEFFCOTT.
